DESIGN FOR A JAR

Henry Guitton, Montreal, Quebec, Canada, assignor to Owens-Illinois Glass Company, Toledo, Ohio, a corporation of Ohio

Application March 22, 1934, Serial No. 51,143
In Canada December 26, 1933

Term of patent 14 years

To all whom it may concern:

Be it known that I, HENRY GUITTON, a citizen of the Dominion of Canada, and residing at Montreal, in the Province of Quebec, and Dominion of Canada, have invented a new, original, and ornamental Design for a Jar of which the following is a specification, reference being had to the accompanying drawing forming a part thereof.

In the drawing:

Fig. 1 is a side elevational view of a jar showing my design.

Fig. 2 is an edge view thereof.

Fig. 3 is a top plan view.

I claim:

The ornamental design for a jar substantially as shown.

Signed at Montreal, in the Province of Quebec, and Dominion of Canada, this 20th day of April, 1934.

HENRY GUITTON.
